UNITED STATES PATENT OFFICE.

JANET R. AIKEN, OF BRANCHVILLE, CONNECTICUT.

CLAY-MODELING BOOK.

Application filed July 28, 1922. Serial No. 578,160.

To all whom it may concern:

Be it known that I, JANET R. AIKEN, a citizen of the United States, and a resident of Branchville, in the county of Fairfield, 5 State of Connecticut, have made certain new and useful Improvements in Clay-Modeling Books, of which the following is a specification.

The main object of the invention is to 10 produce a book which can be repeatedly employed in clay modeling. In other words, the book is constructed so that each page thereof upon which the modeling work is carried out can be used a number of times 15 and still remain in an unspoiled condition.

As illustrating a specific manner in which the invention may be realized, reference is made to the accompanying drawing forming a part of this specification, and in which 20 drawing,

Figure 1 shows the book open; this book is composed of a number of leaves bound together. The leaf at the left constitutes what may be termed an illustrative plate or 25 page, while the leaf at the right constitutes what may be termed the work plate or page.

Figure 2 shows a set of pages, from the book, different from the set prominently appearing in Figure 1.

Figure 3 shows the same set of pages as 30 Figure 2. In Figure 2 the work page appears as it normally exists in the book, while in Figure 3 the work page appears as it exists with the completed model work thereupon.

Reference will now be made to the drawing in detail. The clay modeling book, designated 1, is composed of pages, as 2 and 3, of heavy paper, card-board or other sheet 40 material suitably bound together. When open, as shown in Figure 1, there prominently appears a set of pages the left hand page of which constitutes an illustrative plate or page, so called because there is shown thereupon an object (or objects) to be modeled in bas-relief on the opposite 45 right hand page of the set. This right hand page is specially constructed so as to provide and constitute a work page. The objects illustrated may include geometrical figures, as 4, household articles, figures from 50 nature, as 5, boats, statuary, etc., and they are preferably arranged or graded in the book so that the simple ones appear in the earlier plates and the more difficult ones in the latter plates, whereby if the plates are

consecutively followed there is provided a progressive series of lessons in modeling.

As to each right hand page—the work page—it is constructed as follows: First there is printed thereupon an exact replica 60 of the outline of the design or object appearing on the opposite illustrative page. In fact the outline, as 6, which includes a few main lines, as 7, is all of the design or object that appears on the work page. The 65 working surface—at least—of the work page is then coated with paraffin wax or other suitable coating material which is transparent whereby the design outlined is below the resulting coating, as 8.

In order to facilitate the work of the student or person employing the book it is preferable to use a permanently plastic clay which contains a high percentage of oil to prevent hardening, but it will be remarked 70 that a clay which is mixed with other ingredients may be employed. The object of providing the paraffin or other suitable coating is so that when the modeling clay is placed upon the work page the clay or its 75 mixing ingredients will not soil, stain, penetrate, or render unfit for future use the material of the work page or the design upon it. Such being the case, it will be manifest 80 that the coating must be oil proof where a clay mixed with oil is to be employed in the book. Since paraffin is impervious to water, and also to the oil used in permanently plastic clay, it provides an excellent 85 coating to attain the desired end; however, 90 it will be noted that other protecting coatings could be employed to realize the desired result.

In employing the book the student—or 95 person doing the actual modeling work— places a daub of clay on the work page over the outline, molds it with tools and fingers until it exactly covers the outline, follows the completed picture given on the opposite 100 plate or illustrative page and, step by step, reproduces in actual clay, as at 9, the bas-relief illustrated, as at 5.

Once the design on the waxed page—the 105 work page—is completed the clay may be removed, leaving the page in its original unspoiled condition: the page may be used any number of times for repeated reproductions of the models given or in variations of them as desired.

The invention relates to a clay modeling 110 book having the advantageous features

above outlined and set forth in the accompanying claims. It will be manifest, however, that the invention may be realized in various forms and ways without departing 5 from the spirit and scope thereof.

What I claim is:

1. A book for use in clay modeling work, which book comprises sets of pages each of which sets when open has a left hand illustrative page and a right hand work page, the left hand illustrative page having thereupon a full representation of an object to be modeled in bas-relief on the opposite work page, and which work page has thereupon an outline which is an exact replica of the outlines of the design appearing on the opposite illustrative page, the work surface

of the work page also being coated with paraffin to serve as a protecting coating.

2. A book for use in clay modeling work comprising illustrative plates each having the representation of some object to be molded in clay, and work plates each having an outline of an object shown on the illustrative plate corresponding thereto, that portion of each work plate having the outline being provided with a transparent protecting coating whereby each work plate can be repeatedly used in successive modeling work.

This specification signed this 24th day of July, 1922.

JANET R. AIKEN.
